UNITED STATES PATENT OFFICE

BENJAMIN MINTZ, OF NEW YORK, N. Y.

DESIGN FOR A LOLLYPOP

Application filed August 12, 1931. Serial No. 40,836. Term of patent 8½ years.

To all whom it may concern:

Be it known that I, BENJAMIN MINTZ, a citizen of the United States, residing at New York, in the county of New York and State of New York, have invented a new, original, and ornamental Design for a Lollypop, of which the following is a specification, reference being had to the accompanying drawings, forming part thereof.

Fig. 1 is a front elevational view of a lollypop, showing my new design.

Fig. 2 is an end elevational view of the same.

The opposite sides of the lollipops are the same as the corresponding sides shown on the drawings.

I claim:

The ornamental design for a lollypop, as shown and described.

In testimony whereof I have affixed my signature.

BENJAMIN MINTZ.
